UNITED STATES PATENT OFFICE.

JOSEPH BRESLOVE, OF PITTSBURGH, PENNSYLVANIA.

CONTROL MECHANISM FOR STOKERS.

Application filed April 19, 1920. Serial No. 374,922.

To all whom it may concern:

Be it known that I, JOSEPH BRESLOVE, a citizen of the United States, and a resident of Pittsburgh, in the county of Allegheny and State of Pennsylvania, have made a new and useful Invention in Control Mechanism for Stokers, of which the following is a specification.

This invention relates to control mechanisms and particularly to such mechanisms for use in connection with automatic stokers.

An object of the invention is to produce simple and effective means for controlling the delivery of fuel to an automatic stoker in response to variations in the steam output of the boiler associated therewith. This may be indicated by variations in the pressure or flow of the steam.

A further object is to produce a new and improved control mechanism for automatic stokers which is adapted to control the operation of the fuel feeding apparatus so as to proportion the delivery of fuel to the stoker in response to variations in the amount of blast delivered to the stoker.

A further object is to produce a control mechanism for automatic stokers in which the control of the fuel feeding apparatus is accomplished automatically through the agency of electrical devices and in which manually adjustable means are employed for accelerating or retarding the automatic operation of the fuel feeding apparatus at the will of the operator.

A further object is to produce an automatic mechanism for controlling the operation of the fuel feeding apparatus of an automatic stoker in response to variations in the supply of draft or blast to the stoker, in which means are employed for automatically stopping the fuel feeding operation when the amount of blast delivered falls below a predetermined amount and for automatically starting the delivery of fuel to the stoker when the blast is increased a predetermined amount.

These and other objects which will be made more apparent throughout the further description of the invention are attained by means of apparatus embodying the features herein described and illustrated in the drawings accompanying and forming a part hereof.

In the drawings, Figure 1 is a diagram-

matic view of a stoker equipped with apparatus embodying my invention. Figure 2 is a wiring diagram which may be employed in connection with the apparatus illustrated in Figure 1. Figure 3 is a detail of a part of the apparatus shown in Figure 1.

Where automatic control of stokers or mechanically controlled furnaces is employed, it is customary to control the delivery of blast and the delivery of fuel in response to variations in the amount of steam generated by the boiler or boilers associated with the stoker. This is sometimes accomplished by employing a pressure responsive device which responds to variations in steam pressure and in turn controls the operation of the blast delivery mechanism, or the fuel feeding mechanism, or both. The automatic control is sometimes accomplished in response to variations in the flow of steam from the boiler or boilers in which case a flow responsive device is substituted for the pressure responsive device as the controlling agent of the blast delivery and fuel feeding mechanism. Flow responsive devices have also been employed in connection with pressure responsive devices and the arrangement has been such that the flow responsive device exerts a modifying or controlling effect on the operation of the pressure responsive device. In fact, changes in various operating conditions within the furnace and the boiler have been taken advantage of for the purpose of accomplishing the automatic control of the stokers. In addition, automatic control, in the broad sense, has been applied to a battery of boilers and their co-operating stokers so that the stokers are controlled as a unit. On the other hand individual automatic control of the different stokers associated with such a battery of boilers has been employed. It will be apparent from the foregoing and from the further description that apparatus embodying my invention may be employed with control mechanism of the various types above mentioned and with apparatus arranged to accomplish either individual or unit control of stokers associated with a battery of boilers.

In the accompanying drawings my invention is illustrated in connection with a diagrammatic view of a well known stoker in

which each fuel feeding ram or plunger is actuated by a separate pressure actuated piston.

As shown, the furnace 4 is provided with a plurality of hoppers 5 and each hopper is associated with a separate fuel feeding ram (not shown) which is actuated by means of a double acting piston located within a cylinder 6. Each cylinder is provided with connecting piping 7 through which the steam entering and discharging from the cylinder passes. In the particular form of apparatus diagrammatically illustrated, each cylinder is provided with a control valve which forms a part of an automatic unit diagrammatically illustrated at 8. The separate control valves forming a part of the mechanism 8 are associated with a rotatable shaft 9 and are adapted to be actuated by that shaft. The particular type of valve employed for controlling the operation of the fuel feeding rams is not important, so far as my invention is concerned, and consequently I have not illustrated the valve in detail. It may be said, however, that the valve employed in connection with the type of stoker diagrammatically illustrated may be the Cole automatic valve fully illustrated and described in United States patent to Roe No. 951,340 of March 8, 1910.

In so far as this invention is concerned, it is only necessary to state that the separate control valves of the separate cylinders are embodied in the valve mechanism 8 and that the operation of each independent valve forming a part of this mechanism is controlled by the shaft 9. Consequently the timing of the valve and the rate of operation of the fuel feeding ram associated with the valve is dependent upon and varies with the speed of rotation of the shaft 9.

In the drawings I have diagrammatically illustrated an air duct 10 for delivering air to the furnace. As diagrammatically indicated, the air is delivered to the duct 10 by a fan or blower 11. The blower 11 may be driven by any suitable apparatus, but as illustrated, is shown operatively connected to a steam turbine 12, which receives steam through a supply pipe 13 and an automatic valve 14. It will be, of course, understood that the heat of the exhaust steam from the turbine may be conserved in any of the various ways well known in power plant practice. I have diagrammatically shown an automatic device 15 for controlling the operation of the valve 14 and consequently the speed of the turbine 12. As illustrated, this device may be a pressure responsive device and it may be placed in communication with the steam boilers, associated with the furnace 4, through a pipe or passage 16. With this arrangement, the speed of the turbine and consequently the speed of the blower 11 will vary in response to variations in

the pressure delivered by the boilers, since the device 15 will open and close the valve 14 in response to variations in boiler pressure. It will, of course, be understood that so far as my invention is concerned, the device 15 may be of any type and it may respond in operation to any change in operating conditions within the boiler or associated apparatus. As has been stated, it is desirable to vary the rate of fuel feed in response to variations in the amount of blast delivered to the furnace or in other words it is desirable to vary the rate of fuel feed in response to variations in operating conditions so that the furnace or stoker will respond to a change in operating conditions and will function in such a way as to return the furnace and its associated boiler back to normal operating conditions within a minimum period of time. For this reason, I employ means for varying the operation of the fuel feeding rams in response to variations in the speed of the blast delivery apparatus. To state this more broadly, the apparatus illustrated is provided with means for varying the rate of fuel feed in response to variations in the amount of blast delivered to the furnace.

The means illustrated for accomplishing this result includes an electric generator 17 operatively coupled to the shaft of the fan or blower 11 and so arranged that its speed will vary with variations in the speed of the fan or blower 11. As diagrammatically illustrated, the generator 17 is operatively coupled to the shaft 18 of the turbine which is diagrammatically illustrated as being directly coupled to the shaft of the fan or blower 11. The terminals of the generator are shown electrically connected to conductors 19 and 19'. It will, of course, be apparent that variations in the speed of the generator 17 will occasion variations in current voltage delivered by the generator and that this varying voltage may be employed in occasioning corresponding variations in the speed of rotation of the shaft 9, which forms a part of the automatic valve mechanism 8. As illustrated, the shaft 9 is operatively coupled to an electric motor 20 which receives current from the generator 17. The speed of the motor with relation to the speed of the generator may be proportioned by varying the windings of the motor in a manner well known to electrical engineers, but with the arrangement described, variations in the speed of the generator 17 will occasion corresponding variations in the speed of the motor 20 and consequently in the rate of the delivery of fuel to the stoker, since the operation of each of the fuel feeding rams is dependent upon and is timed by the rotation of the shaft 9.

It will be apparent that the generator 17 may be either an alternating current or a

direct current generator and that the motor 20 may be varied in type and design to suit the current conditions encountered.

Figure 2 is a wiring diagram, showing an arrangement of wiring suitable for use in connection with direct current apparatus. As shown, the generator 17 is a direct current generator and one brush is connected to a wire 21 which is normally electrically connected to one brush of the motor 20. The other brush of the generator is electrically connected to a wire 22 which is normally electrically connected to the other brush of the generator. Under such conditions, the speed of the motor 20 will vary in direct ratio to variations in the speed of the generator 17. A separately excited field for both the generator and motor will preferably be employed. I have indicated a field control rheostat 23 which may be employed in connection with the generator field. As illustrated, the rheostat arm 24 is provided with a handle 25 which may be manually operated for the purpose of varying the position of the arm with relation to the terminals of the rheostat and for thereby varying the speed of the motor 20 independently of variations in the speed of the generator. I have also diagrammatically illustrated a field rheostat in the field 27 of the motor. This rheostat like the rheostat 23 may be adjusted manually to vary the speed of the motor independently of the speed of the generator.

With such apparatus, the motor may be adjusted to run at a predetermined speed when the generator or the blast delivery mechanism is running at normal speed. This adjustment may, of course, be accomplished with the rheostats 23 and 26. Variation in the speed of the blast delivery mechanism will occasion an automatic variation in the speed of the motor and consequently a variation in the rate of fuel delivery.

In the drawings I have shown an automatic switch 28 adapted to open the operating circuit of the motor 20 when the speed of the generator 17 falls below a predetermined speed. The device 28 preferably consists of a solenoid connected across the terminals of the generator and having its armature so arranged that a predetermined voltage will close the switch, whereas, a drop in voltage below a predetermined value will permit the plunger to be withdrawn by means of a spring 30 for the purpose of opening the switch (see Fig. 1). With such an arrangement, the solenoid will operate to open the switch and stop the motor when the voltage falls below a predetermined value and will close the switch after the voltage has increased above a determined value. Under such conditions, the fuel feed will be automatically cut off when the blast or draft has

been reduced to an amount which merely holds a banked fire, and will automatically start up as the blast or draft is increased.

Having thus described my invention, what I claim is—

1. In combination with a furnace and the boiler associated therewith, a blast delivery mechanism, means responsive to changes in the steam output of the boiler for driving said blast delivery mechanism, an electric generator operatively connected to said means, a fuel feeding mechanism, means for controlling the operation thereof, and electrical apparatus responsive in operation to variations in the speed of said generator for controlling the operation of said last mentioned means.

2. In combination with a furnace and the boiler associated therewith, a fuel feeding mechanism, automatic means for controlling the delivery of blast to the furnace in response to variations in the steam output of the boiler, an electric motor for controlling the operation of said fuel feeding mechanism, means responsive to variations in the amount of blast delivered to the furnace for varying the speed of the motor, and automatic means for cutting off the operating current to the motor when the blast delivery falls below a predetermined amount and for delivering current to the motor when the blast delivery increases above a certain amount.

3. In combination with a stoker and the boiler associated therewith, a blast delivery mechanism, means responsive to variations in the steam output of the boiler for driving said blast delivery mechanism, an electric generator driven by said means, a fuel feeding mechanism, means for controlling the operation thereof, an electric motor receiving current from said generator for controlling the operation of said fuel-feed controlling means and manually controlled means for varying the speed of said motor independently of variations in the speed of said generator.

4. In combination with a furnace and the boiler associated therewith, a fuel feeding mechanism forming a part of the furnace, a valve mechanism for controlling the operation of said fuel feeding mechanism, a fan for delivering blast to the furnace, apparatus for driving the fan, an electric generator operatively coupled to said apparatus, an electric motor receiving current from said generator and controlling the operation of said valve mechanism, and automatic means responsive to variations in the steam output of the boiler for controlling the speed of said apparatus and thereby controlling the delivery of blast and the rate of fuel feed to the stoker.

5. In combination with a furnace and the boiler associated therewith, a blast delivery

- mechanism, means for driving said mechanism at variable speeds, an electric generator driven by said means, a fuel feeding mechanism, means for controlling the operation 5 of said mechanism and a motor for driving said controlling means receiving current from said generator and adapted to increase and decrease in speed in response to increases and decreases in the speed of said 10 generator.
6. In combination with a furnace and the associated boiler, a blast delivery mechanism, means responsive to changes in the steam output of the boiler for driving said 15 mechanism, a fuel feeding mechanism, means for controlling the operation thereof, and interconnected electrical apparatus for controlling the operation of said last-mentioned means in response to variations in 20 the speed of said blast delivery mechanism including a generator driven by said driving means and a motor receiving current therefrom and driving said feed mechanism controlling means.
- 25 7. In combination with a furnace and the associated boiler, a blower for delivering air under pressure to the boiler, driving means therefor, means responsive to variations in the steam output of the boiler 30 for varying the speed of said driving means, an electric generator operatively coupled to
- said driving means and adapted to vary in speed therewith, a fuel feeding mechanism, timing means for controlling the operation thereof, a motor receiving current from said generator and adapted to vary in speed in response to variations in current voltage occasioned by variations in the speed of said generator, for controlling the operation of 35 said timing means. 40
8. In combination with a furnace and the boiler associated therewith, a fuel feeding mechanism for delivering fuel to the furnace, a fan for delivering blast to the furnace, driving means for said fan, means responsive to variations in the steam output of the boiler, for controlling the speed of said driving means, an electric generator operatively connected to said driving means and adapted to vary in speed therewith, automatic means for controlling the operation of said fuel feeding mechanism, an electric motor receiving current from said generator and adapted to vary in speed in response to variations in current voltage occasioned by 45 variations in the speed of the generator for controlling the operation of said automatic means. 50

In testimony whereof, I have hereunto subscribed my name this 17th day of April, 1920.

JOSEPH BRESLOVE.
